Patented Sept. 11, 1928.

1,684,067

UNITED STATES PATENT OFFICE.

JOHN C. MOON, OF ST. LOUIS, MISSOURI.

DUST COLLECTOR.

Application filed February 17, 1926. Serial No. 88,815.

My invention relates to dust collectors such as are adapted to be used particularly in shoe repair or finishing machinery in which one or more sanding and scouring 5 wheels are used, each of which is usually provided with a chute connection to a blower which carries the dust from the wheels to a discharge point.

The dust produced by the machine is frequently discharged outside of the building 10 but this is not always practical, and it is desirable to use a dust collector by means of which the dust may be removed from an air stream passing therethrough and the air discharged into the operating room.

The general object of my invention is to provide an efficient collector for the purpose mentioned, and the detail objects of my invention are to provide a collector which may 20 be mounted on the ordinary finishing machine, which will include an easily filled and cleaned water chamber through which air may be passed, and which may be connected at either end to the blower according to the 25 relative location of the blower and dust collector.

In the accompanying drawings which illustrate a preferred embodiment of my invention,—

30 Figure 1 is an elevation of a finishing machine and viewing the same from the front of the finishing machine with my collector shown thereon in longitudinal section.

Figure 2 is a vertical cross section through 35 my dust collector, taken on line 2—2 of Figure 1 and showing the adjacent parts of the finisher frame.

The upright frames of the finisher are indicated at 1 and they are connected by 40 horizontal pipes 2 and 3 forming parts of the finisher framing. The frame mounts the operating shaft 4 which is located a short distance above lower frame elements 2. The frame also mounts the wheel carrying shaft 5. All of the above-mentioned 45 parts are of ordinary construction and form no part of my invention.

The dust collector is of box-like structure and comprises front and back walls 6 and 50 7, respectively, end walls 8, a top wall 9, and a bottom wall 10. The bottom wall is offset intermediate the front and back of the collector to form a depression 11 adapted to hold water, and the bottom wall at the rear 55 of depression 11 is inclined toward the depression so that any water in the rear por-

tion of the collector will drain into the depression. The end walls 6 and 7 are provided with suitable openings through which an intake pipe 12 may pass, pipe 12 being 60 open at both ends with each end adapted to have a cap 13 applied thereto or to be connected to a blower 14 by means of an elbow 15 or the like.

The lower portion of pipe 12 is provided 65 with an opening to receive a downwardly extending conduit 16, the lower end of which projects below the top of the water chamber forming depression 11 in the front of the box. The conduit is inclined forwardly 70 somewhat to bring its mouth in the center of the water chamber.

Behind pipe 12 I provide a longitudinal upright baffle 17 shown as extending from end to end of the collector and having its 75 lower edge spaced a short distance above the bottom wall 10 to permit drainage thereunder. The upper edge of the baffle is spaced a substantial distance from the top of the box and is provided with a horizontally forwardly extending flange 18 terminating in a return bend 19.

Behind and spaced from baffle 17 I provide a second baffle 20 extending downwardly from the top of the box and having a 80 lower flange 21 with a return bend 22. Behind baffle 20 the top of the collector is provided with an opening to permit the discharge of air passed through the device. Air forced into the collector through pipe 90 12 passes downwardly through the water in depression 11 and then upwardly over baffle 17 and then downwardly under baffle 20 and then upwardly into the room. The tortuous 95 passage provided for the air and the flanges on the baffles are adapted to intercept and collect any drops of water which would otherwise be likely to be carried through the device by the air stream.

The depressed portion of the collector forming the water chamber is provided with a drain plug 23 and an overflow plug 24 and the top of the collector is provided with a removable cover 25. These elements render it easy for the ordinary workman using the 100 finishing machine to empty and refill the water chamber when desired.

The offset bottom of the collector, besides providing the water chamber, adapts the device for clearing the operating shaft 4. The 110 collector may be supported by suitable U-shaped straps 26 on the upper frame ele-

ments 3. The bottom of the collector is inclined from the drain plug and upwardly toward the opposite end to facilitate cleaning of the device.

5 I direct attention to the fact that the sectional areas of the conduit 16 and of the passage from the conduit and around the sides of the same and to the discharge opening and the area of the latter are all substantially larger than the sectional area of pipe 12. The air stream forced through the pipe is thereby diminished in intensity as it enters and passes through the collector and this results in less agitation of the water, 10 in more thorough cleansing of the air, and in more effective baffling of the air stream so as to collect the water mist from the stream. The flange 21 on baffle 20 is perforated to permit passage of water therethrough and 15 the functioning of the return bend 22 is thereby maintained.

The arrangement and proportion of the parts as illustrated has been tested and found to be highly efficient in removing dust 25 collected by the blower, but obviously various modifications in the details of my collector may be made without departing from the principles thereof, and I contemplate the exclusive use of such modifications as are 30 included in the scope of my claims.

I claim:

1. In a dust collector, a closed box having an opening in one side of its top and an air inlet pipe extending through said box from end to end and located near the opposite side of the box, a water holding depression in the bottom of said box beneath said pipe, a conduit on said pipe leading into said depression, an upright longitudinal baffle spaced slightly from the bottom of said box and having a horizontal top flange below the top of the box and extending toward said pipe, a second upright longitudinal baffle between said first mentioned baffle and said top opening extending downwardly from the top of said box and having a horizontal lower flange above the bottom of the box and extending toward said first mentioned baffle.

50 2. In a dust collector, a closed box having an opening in one side of its top and an inlet pipe extending through said box from end to end and located near the opposite side

of the box, a water holding depression in
the bottom of said box beneath said pipe,
a conduit on said pipe leading into said
depression, an upright longitudinal baffle
spaced slightly from the bottom of said
box and having a horizontal top flange be-
low the top of the box and extending toward
said pipe, a second upright longitudinal baffle
between said first mentioned baffle and
said top opening extending downwardly
from the top of said box and having a hori-
zontal lower flange above the bottom of the
box and extending toward said first men-
tioned baffle, each of said flanges having a
return bend on its longitudinal edge for
trapping water in air striking against said
flanges.

3. In a box-like dust collector, a chamber for a body of water at one side occupying a relatively small portion of the box space, an inclined floor leading from the other side of the collector downwardly to said chamber, there being a discharge opening in said collector at the side opposite said chamber, an air intake conduit for conveying an air stream and discharging the same into said chamber below the top thereof, the walls of the collector forming an air discharge passage leading from above said chamber over said inclined floor, vertically extending and vertically staggered baffles in said passage spaced above said floor for collecting water from air passing from said chamber and for discharging said collected water to said inclined floor where it may flow back to said chamber. 75 80 85

4. In a dust collector, a chamber for a body 90
of water, an air intake pipe extending
through the collector from side to side above
said chamber and adapted to be opened
at either end, readily removable means for
closing the opposite end of said pipe, a con- 95
duit from said pipe extending below the
top of said chamber, a passageway for air
leading from the sides of said conduit to
the exterior of the collector, and baffles in
said passageway for collecting water car- 100
ried by the air stream moving from said
chamber to the exterior of the collector.

In testimony whereof I hereunto affix my signature this 12th day of February, 1926.

JOHN C. MOON.
